TION OF NEW YORK.

COMBINED TYPE-WRITING AND COMPUTING MACHINE.

1,203,988.

Specification of Letters Patent.

Patented Nov. 7, 1916.

Application filed December 23, 1911. Serial No. 667,464.

To all whom it may concern:

Be it known that we, GUSTAVE O. DEGENER and ELIAS SAUNDERS, both citizens of the United States, and residing in the city, 5 county, and State of New York, have invented certain new and useful Improvements in Combined Type-Writing and Computing Machines, of which the following is a specification.

10 This invention relates to special forms of computing mechanism, and is herein described as applied to a combined typewriting and computing machine of the Underwood-Wright type and as adapted to compute in English or sterling money.

15 In most computing machines the mechanism is limited to numbers employing the decimal system of notation. In English money, for example, there are twelve pence to one shilling and twenty shillings to one pound, and no ordinary computing machine will properly write and add such money without various complicated manipulations on the part of the operator. This invention

25 is designed to enable such computations to be performed with ease and rapidity.

The invention consists in one aspect of providing a special key which is arranged to operate a type printing one number, but 30 computing another in the computing mechanism. This key is in addition to the key which normally writes said number and computes the identical number.

In the specific form here illustrated, certain keys are in such a combination with the platen shift mechanism which controls the relation of the platen to the type, that by shifting the platen, ten or eleven pence may be written in, in ordinary figures, while at 35 the same time, the computing mechanism without any alteration, adds in the corresponding numbers to the computing machine. Here the result is accomplished without adding any special keys to the ordinary 40 key-board of a case-shift writing machine and without the highly complex mechanism sometimes employed. On the upper case of the type heads bearing "5" and "6" may be placed a figure "1" and the type keys are 45 correspondingly marked, and on the upper case of type head bearing figure "4" may be placed "0" and its key is marked to

correspond. Then to add and write ten pence it will be sufficient to depress the platen shift key, strike the numeral key 55 bearing "6" in its lower case and then the numeral key bearing "4" in its lower case. Similarly to write eleven pence, depress the case-shift key and strike the key bearing "6" in its lower case and then the key bearing "5" in its lower case which add to 60 eleven, and since the 5 and 6 keys are arranged to print "1" in upper case, the keys will also write "11".

In application 652,532, filed October 3, 1911, a master wheel moves step by step with the typewriter carriage, successively engaging gears which rotate the computing wheels and rotating them to an extent regulated by the numeral keys. Tens carrying mechanism is provided between the successive computing wheels. In the present invention when the shillings column is reached an alteration may be made in the carrying over mechanism. This is so arranged that 70 the carrying over wheel for the tens shillings column will operate at every alternate unit space, thus adding in a pound for every twenty shillings recorded. In the pence column a broad numeral wheel may be provided, having two columns and engaging a correspondingly broad gear wheel which is driven by the master wheel and which gear is controlled by that master wheel precisely 75 as are the ordinary decimal gears. This gear is so related to its dial wheel that each unit movement of the master wheel rotates this dial wheel one twelfth of a revolution, namely; one unit. Therefore the largest numeral key "9" will only turn this dial wheel 80 nine units or twelfths of a revolution. Ten pence and eleven pence are computed by operating more than one numeral key; and since this pence gear covers two letter 85 spaces, the master wheel will engage it while two numeral keys are successively struck in the normal operation of the machine, and compute them both in the pence column. One convenient method of arranging numeral keys has been described above for thus 90 computing ten and eleven pence.

The carrying of a shilling at each twelve pence is accomplished by changes in the carrying-over mechanism. In some aspects this

invention may be regarded as an improvement on the co-pending case No. 652,532 filed October 3, 1911.

Other features and advantages will hereinafter appear.

In the accompanying drawings, Figure 1 represents a side view of an Underwood-Wright computing machine, showing so much thereof as is necessary to understand the present invention. Fig. 2 is a skeleton perspective view of the connection between the numeral keys and parts of the computing mechanism. Fig. 3 is a section through the casing containing the computing wheels, and some other allied parts. Fig. 4 is a section showing the tens of shillings wheel together with some of its connecting gearing. Fig. 5 is a similar perspective view of the pence wheel. Fig. 6 is a diagrammatic view showing the relation between the numeral keys and the types which they control. Fig. 7 is a view of the computing head partly broken. Fig. 8 is a section of the same. Fig. 9 is a diagrammatic view of an alternative arrangement of numerals. Fig. 10 is a diagrammatic view of another arrangement of numerals.

In the Underwood-Wright type of combined typewriter and adding machine, letter keys 1 and figure keys 2 depress levers 3 having returning springs 4. These levers are connected, by means of bell cranks 5, to type bars 6, which are swung up to strike against the face of a platen 7. The type bars are pivoted upon a fulcrum wire 8 and have heels 9 to press rearwardly a universal bar 10, which is mounted on a frame 11 to operate dogs 12, 13, which coöperate with an escapement wheel 14 connected with a pinion 16 to mesh with a rack 17 upon a carriage 15 which carries said platen 7; the carriage being driven by a spring barrel 18.

Each figure key 2 is also connected by a hook 19, a lever 19^a, and a link 20, (Fig. 2), to a lever 21 pivoted at 22 and forming one of a series of levers grouped radially, and each carrying a jack 23 to displace, namely set up, computing pins 24 in a power driven wheel 25. This wheel is driven by a constantly rotating motor 26, connected by gears 27, 28, 29, 30 and 31, to said wheel 25, and tending constantly to turn the latter; a friction safety clutch 32 being interposed between the motor and the wheel 25. A four toothed pinion 33 fixed to an escapement wheel 34, intercepts the path of the pins when projected as they turn with wheel 25. This escapement wheel, (Fig. 1), is controlled by dogs 35, 36, fixed upon a rock shaft 37, which is also controlled by the figure keys 2; and each of the levers 21 has an arm 38 to bear against a disk 39, which is connected to lever 40 having a pivot between its ends as at 41, and connected by a link 42 to an arm 43 fixed upon rock shaft 37.

When any key 2 is depressed, it rocks the shaft 37 in one direction, allowing the teeth of wheel 34 to slip off from the dog 35 onto dog 36; and when the key returns, the shaft is rocked in the other direction by means of spring 44, (Fig. 2), thereby enabling the escapement wheel 34 to slip off the dog 36, so that the pin carrying wheel 25 is permitted to rotate until the next projected pin thereon comes into engagement with the pinion 33. After each pin is used, it is restored to normal position by suitable means, not shown.

To the pin carrying wheel 25 is geared a shaft 45 of a master wheel 46; the connection including gears 47, 48, 49, 50, 51 and 52, the latter fixed upon the shaft 45, to which the master wheel is splined.

The master wheel has opposite teeth 53 to engage internal gears 54, (Figs. 4, 5), formed upon computing wheels 55, the latter having gears 56 meshing with gears 57 provided upon dial wheels 58.

The rotative movement of the pin carrying wheel 25 is transmissible to any of the dial wheels. These dial wheels are mounted in a casing 59 which is secured upon the framework of the machine. The master wheel 46 is connected to a tubular arbor 60, which is connected to the carriage 15 of the typewriter, to move step by step therewith; the connection comprising a lever 61 pivoted at 61^a midway between its ends, and connected at its forward end to said tube 60, and at its rear end to the carriage by one or more lugs 63 on a bar 62 carried by the carriage. The master wheel 46 travels to the right, (Fig. 8), as the carriage 15 travels in letter feeding to the left; the writing and adding proceeding from the higher to the lower denomination.

Upon each of the computing wheels 55, is a special tens-carrying tooth 64, which once in each revolution engages and rotates a five toothed pinion 65, fixed to which is an ordinary pinion 66 meshing with the gear 56 of the next higher denomination, whereby tens are carried upon the latter.

To assist at the tens-carrying operation, there is provided a mutilated assisting gear 67 which comprises five sets of teeth at equal intervals. The mutilated gear 67 which is fast to the pinions 66 and 65, is arranged to be engaged by one of a series of constantly rotating pinions 68, which are fixed upon a shaft 69, the latter being connected to the constantly rotating motor 26 by means of a train of gears designated generally as 70. The special tooth 64 on the computing wheel 55 rotates the mutilated gear 67 enough to engage it with the constantly rotating pinion 68; the latter thereupon drives the mutilated gear, with its two connected pinions, until the tens-carrying operation is substantially completed. A

spring detent 71 for each mutilated gear, snaps into a seat 72, of which five are provided upon each mutilated gear 67 of a decimal dial wheel, and holds the figures 5 on the dial wheels alined.

In order to accomplish the carrying of pence into shillings and shillings into pounds, the special carrying tooth, herein described before as 64, must have a different relation to the carrying mechanism than one to ten. In carrying pence into shillings, the shillings dial wheel must only be advanced one number every twelfth penny, while in the addition of shillings, the 10 pounds dial wheel must be advanced one number every twentieth shilling. Therefore the mechanism for the computation of pence and shillings is constructed as follows: The pence dial wheel 73, which is a combination 15 of two dials fixed to each other, has twelve divisions or readings, between which there is a gear 73^a meshing with gear 73^b formed on an idle collar 55^a on the pence computing wheel 55. The gears 73^a and 73^b are 20 of the same size, and the collar 55^a serves to align the pence wheel in a manner to be later described. As there are twelve divisions on the pence wheel, said wheel will accordingly have to be moved in twelfths of 25 a revolution, and as the master wheel moves the gear 74 in units of one tenth of a revolution, the ratio between the gear 74 and the gear 73^d is accordingly ten to twelve.

It will be seen in Fig. 8, that the internal 30 gear 54^a, which is the driver of the pence wheel 73, is twice the width of the ordinary internal gear 54, for when there are ten or eleven pence to be added, two digits or figures are printed in adjoining letter 35 spaces, causing two computations to be made on the same dial, and the master wheel must engage with the gear in each letter space. The printing of ten pence and eleven pence is done as described below.

40 The machine herein illustrated, as is usual in Underwood typewriting machines, comprises a platen shift key 76 which depresses a lever 77 to throw a bell crank 78 at the rear of the machine, which carries a shift 45 rail 79. On this shift rail runs a wheel 80 which, through an arm 81, is arranged to shift the platen frame 82, so that the types 50 in the lower and upper case strike the paper on the platen 7. Normally the lower 55 case types 84 strike the platen. The numeral keys 2 have on them each two figures 60 and 86 corresponding respectively to the upper and lower case types, so that when it is desired to write in the upper case, the 65 platen shift key 76 is depressed; then while this key is held depressed, a type key is struck and the upper figure 83 on the type will make its imprint on the work.

In the machine shown as illustrated in Fig. 6, the depression of the platen shift

key 76 in no way alters the computing mechanism *per se*. But the numeral key 2 bearing the character "4" has marked on it in its upper case a "0"; the numeral key 2 having its lower case marked "5", has its upper 70 case marked "1", and the numeral key 2 having its lower case marked "6", likewise is marked "1", and these keys operate types which are correspondingly made. If now, the machine stands at a position to write in 75 the tens space in the pence column, and it is desired to write ten pence, a number "1" may be written therein by depressing the platen shift key and striking the type key bearing the number "6" in its lower case; 80 then as has just been described, the type will imprint a "1" in that space. Then while holding the platen shift key depressed, if the key bearing the number "4" is struck, a "0" will be written. Thus while the figures 85 composing the number "10" have been written, the numbers six and four forming ten, have been added in, because the computing mechanism has been acting precisely as if the platen shift key had not been operated. 90 In the same way, if it is desired to write "11" in the pence column, the key bearing the lower case "6" is struck while the platen shift key is depressed and the key bearing the lower case "5" is struck with the platen 95 shift key depressed. Then it is apparent that "1" will be written twice with a letter-space interval in the pence column, showing "11" pence, while at the same time, six and five have been added in the computing mechanism thus making eleven added in and recorded.

When the computations on the pence dial have reached twelve, the dial wheel 73 will have made a complete revolution, and the 100 sum amounting to one shilling, is carried to the shillings dial wheel 58^a as follows: During the rotation of the pence dial 73, the gear 73^a, between the two columns of the dial wheel 73 and fast to said dial wheel, 105 rotates the gear 73^b which carries a broad tooth 73^c, that in passing, strikes and starts to turn a toothed star wheel or pinion 65. This pinion 65 has fast to it a pinion 66 which constantly engages a gear 56 on the 110 units of shillings wheel, and also comprises seats 72 for a detent 71. Thus said pinion has the same construction and the same functions as the pinion 65, hereinbefore described in the tens carrying of the totalizer, 115 but as seen in Fig. 8, the hub of this carry-over pinion is elongated to correspond to the breadth of the collar 55^a.

To prevent an overthrow of the pence dial wheel, a spring detent 71 (Fig. 8), like that 120 provided for the decimal wheels, snaps into a seat 72^a, of which there are six provided upon a special detent wheel 67^a. Said detent wheel 67^a is fixed to a gear 67^b in mesh with the collar gear 73^b, which gear 67^b be- 125

ing one half the size of the collar gear 73^b, travels twice as fast, and so turns two-twelfths or one sixth of a revolution, for every unit represented by the key struck for the computation. Thus the detent 71 justifies the pence dial for each twelfth of a revolution.

To compute shillings, an ordinary dial wheel 58 is used in the unit column 58^a having the same tens carrying arrangements as the usual decimal form, but in the tens column of shillings, the dial wheel 58^b, has the numerals reading, 1, 0, 1, 0, 1, 0, etc., while the computing wheel 55 has five broad teeth 64, so that it carries into the unit pounds column at every second unit movement. The pounds are computed on the decimal form of totalizer. In order to allow the broad teeth 64 and 73^c to pass the dial wheels without tending to lock them, a hollow 75 is provided for each of said broad teeth into which they may go.

It will be noted that while the mechanism is described as being adapted for computing English money, it may be also used for computing in twelfths. To do this the operation of the keys is identical with that described for writing pence. For writing twelfths and computing them properly it will be found best to arrange the mechanism so that the last digit of the numerator of the twelfths is at the last computing wheel. Then a diagonal is written on the work sheet, to divide the numerator from the denominator, and afterward a "1" and "2" are written in as denominator. If the computing mechanism is set as just described the denominator, although written on the work sheet, will not be added in. Hence the twelfths may be directly read from the computing wheels. For example 1 10/12 is written, and this will be properly computed if the computing mechanism and typewriter are so arranged that the zero falls in the last letter space in the last column in which computing is done. In that case, the denominator of the number will not be added into the computing mechanism.

In Fig. 9, an alternative arrangement of the numerals on the keys is shown in which the "1" for writing the tens figure of the numerator of twelfths or of shillings, is placed in the upper case of "4;" the zero in the upper case of "6," and "1" in the upper case of "7." This latter "1" is only used in writing the second "1" of "11." The type heads operated by these numeral keys are respectively made to correspond. Other arrangements will be obvious to those skilled in the art.

It will be observed that the invention is not limited to computing twelfths. In Fig. 10, is shown an arrangement of numerals for computing of sixteenths. This might be equally used for computing in Indian

money, in which sixteen annas make one rupee. Other arrangements of keys for computing other kinds of units will also be obvious to those skilled in the art. Of course, in all cases, the type heads must be made to correspond to the numeral keys, and where units other than twelfths are used, corresponding changes must be made in the numeral wheels and carrying-over mechanism. In other words the present invention is directed to enabling numbers to be computed to more than one base, twelfths being numbers to the base twelve, sixteenths to the base sixteen, etc.

Variations may be resorted to within the scope of the invention, and portions of the improvements may be used without others.

Having thus described our invention, we claim:

1. In a computing machine, the combination with a single set of digit keys, of computing wheels, a common drive engaging said computing wheels to carry into each a single digit as recorded by said keys, another computing wheel arranged to receive two digits from said common drive, and means controlling said common drive exclusively from said digit.

2. A key for a typewriting and computing machine bearing the numerals "4" and "0," and connections whereby said key selectively prints either, but always computes the same.

3. A key for a typewriting and computing machine bearing the numerals "5" and "1," and connections whereby said key selectively prints either, but always computes the same.

4. A key for a typewriting and computing machine bearing the numerals "6" and "1," and connections whereby said key selectively prints either, but always computes the same.

5. The combination with a computing mechanism, of a typewriting mechanism having solely a set of nine digit or numeral keys, including both a numeral key arranged to cause an actuation of said computing mechanism according to a predetermined amount, and a second numeral key arranged to cause the actuation of said computing mechanism according to a predetermined amount, and means to enable said numeral keys when actuated in succession to print a two-figured number, the individual digits of which differ from the predetermined amount which the corresponding keys cause said computing mechanism to compute and whose digits taken together represent an amount bearing a definite relation to the aggregate computing effect caused by both said numeral keys.

6. The combination with a computing mechanism, of a typewriting mechanism having solely a set of nine digits or numeral

keys including a pair of numeral keys connected to actuate both said computing mechanism and said typewriting mechanism, the keys of said pair each causing an actuation 5 of said computing mechanism corresponding to its own individual value, and means to enable said typewriting mechanism to print at the successive actuations of said pair of numeral keys, a two-figured number 10 whose individual digits differ from the values of the corresponding keys which print them, and which number as a whole represents the sum of the combined computation caused by said successively operated 15 keys.

7. The combination with a computing mechanism, of a typewriting mechanism, a single set of digit printing keys ranging from "1" to "9" arranged to operate said 20 computing mechanism to compute in an ultra-decimal system, said numeral keys being arranged to cause actuations of said computing mechanism amounts corresponding 25 to their direct values, and shifting means for enabling certain of said keys to print with said typewriting mechanism digits corresponding to their direct values and other digits differing from their direct values, said keys being combinatively actuatable in 30 a plurality of pairs, so that when the keys of a pair are actuated in succession, the individual digits printed concomitantly with their actuation and differing from the normal values of the corresponding keys will 35 combine to designate the sum of the normal values of such keys.

8. The combination with a computing mechanism, of a typewriting mechanism, a single set of digit printing keys ranging from "1" to "9" arranged to operate said 40 computing mechanism to compute in an ultra-decimal system, said numeral keys being arranged to cause actuations of said computing mechanism amounts corresponding 45 to their direct values, and shifting means for enabling certain of said keys to print with said typewriting mechanism digits corresponding to their direct values and other digits differing from their direct values, said keys being combinatively actuatable in a plurality of pairs so that when the keys of a pair are actuated in succession, the individual digits printed concomitantly with their actuation and differing from the 50 normal values of the corresponding keys will combine to designate the sum of the normal values of such keys, certain of said 55 keys being usable in different paired combinations and being capable of representing one of the figures of a two-figured result brought about by the successive actuation of the two paired keys in each pair in which it is applicable.

9. The combination with a series of computing wheels arranged to compute numbers

decimally, of a computing wheel arranged to compute numbers ultra-decimally where the exchange value to the next higher order is greater than ten, a set of nine numeral keys and a master wheel for driving said computing wheels successively controlled exclusively as to the extent of its rotation by said nine keys, each of said computing wheels having a gear engageable by said master wheel, the gear on said ultra-decimally computing wheel being of greater thickness than those of the decimally-computing wheels so as to enable it to be rotatively engaged by said master wheel at two separate points successively in computing a number equal to or greater than ten, the amounts added at each of such rotations being less than ten.

10. The combination with a computing mechanism, of a typewriting mechanism, a series of numeral keys including digit keys "6" and "4," the digit key "6" being arranged to actuate said computing mechanism to compute six and to actuate said typewriting mechanism to print "1," and the digit key "4" being arranged to actuate said computing mechanism to compute four and to actuate said typewriting mechanism to print "0."

11. The combination with a computing mechanism, of a typewriting mechanism, a series of numeral keys for actuating both said typewriting mechanism and said computing mechanism, said numeral keys including digit keys "6" and "5," and means to enable said "6" digit key to actuate said computing mechanism to compute six and to actuate said typewriting mechanism to print "1," said means also enabling said "5" digit key to actuate said computing mechanism to compute five and to actuate said typewriting mechanism to print "1."

12. The combination with a computing mechanism, of a typewriting mechanism, a series of numeral keys for actuating both said computing mechanism and said typewriting mechanism, said numeral keys having values ranging from "1" to "9," and means to enable two of said numeral keys, the sum of whose values equals ten, to actuate said computing mechanism to compute ten by successively adding their respective values and also to enable said typewriting mechanism to print "10," one of said keys enabling the printing of the "1" and the other of said keys enabling the printing of the "0" of the two figures comprising the "10."

13. The combination with a computing mechanism, of a typewriting mechanism, a series of numeral keys for actuating both said computing mechanism and said typewriting mechanism, said numeral keys having values ranging from "1" to "9," and means to enable a pair of said keys, the sum of whose values is eleven, to actuate said

computing mechanism to compute eleven by the adding successively of the respective values of such keys and enabling said keys to actuate said typewriting mechanism to print "11," each of said keys controlling the printing of "1."

14. The combination with a computing mechanism, of a typewriting mechanism, a series of numeral keys for actuating both said computing mechanism and said typewriting mechanism, said keys having values ranging from "1" to "9," two of said keys, the sum of whose values equals ten, paired to actuate said computing mechanism to compute ten by adding successively the values of such keys, and actuating said typewriting mechanism to print "10," one of such keys enabling the printing of "1" and the other of said keys enabling the printing of "0" of "10," and two of said keys, whose sum equals eleven, pairing to actuate said computing mechanism to compute eleven by the successive adding of the values of these latter paired keys, and actuating said typewriting mechanism to print "11," each of said latter paired keys controlling the printing of "1."

15. In a typewriting and computing machine, the combination, with an ultra-decimal computing wheel, and a drive therefor; of a pair of numeral keys operable in succession to print the digits of a two-digit number and cause the complete computation of such number on said wheel, each of said keys acting to compute a digit different from the one which it actually prints, the sum of the digits so computed exactly equaling the number printed.

16. In a typewriting and computing machine, the combination, with a set of computing wheels, including decimal and ultra-decimal wheels, and a drive for said wheels; of a set of nine numeral keys solely controlling the extent of rotation of all of said wheels and including a pair of keys operable in succession to print the digits of a two-digit number and to cause the complete computation of such number on the ultra-decimal wheel: each key of said pair causing the positive drive of said ultra-decimal wheel a predetermined fractional part of the number so computed.

17. In a typewriting and computing machine, the combination, with a set of computing wheels, including decimal and ultra-decimal wheels, and a drive for said wheels; of a set of nine numeral keys solely controlling the extent of rotation of all of said wheels and including a pair of keys operable in succession to print the digits of a two-digit number and to cause the complete computation of such number on the ultra-decimal wheel; one key of the pair acting to print one of the digits of the number and to compute a different digit on the ultra-

decimal wheel, and the other key of the pair acting to print the other digit of the number and likewise to compute a different digit on said ultra-decimal wheel; each key of the said pair acting to print a digit, and to compute the same digit on the decimal wheels.

18. In a typewriting and computing machine, the combination, with a set of computing wheels, including decimal and ultra-decimal wheels, and a drive for said wheels; of a set of nine numeral keys solely controlling the extent of rotation of all of said wheels and including a key operable to print a given digit and to compute the same digit on any one of said wheels, and also including a pair of keys operable in succession to print the digits of a two-digit number and to cause the successive computation on the ultra-decimal wheel of two digits which are both less than ten, and which differ from the digits of the number actually printed, but which exactly total such number.

19. In a typewriting and computing machine, the combination, with a set of computing wheels, including decimal and ultra-decimal wheels, and a drive for said wheels; of a set of nine numeral keys solely controlling the extent of rotation of all of said wheels; and a case-shift mechanism controlling upper and lower case printing by said keys; said set of keys including a key operable to print and compute a given digit, and a second key operable to print the same digit as the first key in upper case and another digit in lower case, but always computing the said other digit.

20. In a typewriting and computing machine, the combination, with a set of computing wheels, including decimal and ultra-decimal wheels, and a drive for said wheels; of a set of nine numeral keys solely controlling the extent of rotation of all of said wheels; and a case-shift mechanism controlling upper and lower case printing by said keys; said set of keys including a key operable to print a given digit in one case and compute that digit on the ultra-decimal wheel, and also operable to print a different digit in the other case, but to compute the first digit on said ultra-decimal wheel.

21. In a computing machine, the combination, with a set of computing wheels, including decimal and ultra-decimal wheels, and a drive for said wheels; of a set of nine numeral keys solely controlling the extent of rotation of all of said wheels, and including a pair of keys each of which is operable individually upon any one of said wheels to compute a given digit thereon, and both of which are operable consecutively upon the ultra-decimal wheel to jointly compute thereon a two-digit number which equals the sum of the separate digits.

22. The combination of a master wheel; a computing wheel, said wheels being rela-

- tively movable step by step, and said computing wheel being operable by said master wheel in two consecutive step-by-step positions, thereby to add upon said computing wheel amounts corresponding with the two consecutive rotations of said master wheel; numeral keys to control said master wheel; a case-shift mechanism; and means to enable said keys to print at the operation of said 5 case-shift mechanism a number corresponding to the sum of the separate amounts added upon said computing wheel at the two consecutive operations of said keys, whereby a number comprising two digits may be 10 printed upon the work-sheet, and a corresponding number added into the totalizer by means of said computing wheel, by reason of the successive additions performed thereon by the master wheel at the successive operations of the keys to print said number. 15
23. In a typewriting and computing machine, the combination, with a plurality of computing wheels, and a drive therefor; of a set of nine numeral keys solely governing 20 the extent of drive; and a case-shift mechanism for controlling upper and lower case printing; certain of said keys adapted to print different digits in upper and lower case, but always computing the digits in 25 lower case, so that when actuated in succession to print a two-digit number in upper case, the digits successively computed by said keys will differ from those of the number actually printed, but will aggregate an 30 amount bearing a prescribed relation to such number. 35
24. In a typewriting and computing machine, the combination, with a plurality of computing wheels, including an ultra-decim- 40 al wheel, a master wheel for driving the computing wheels *seriatim*, and a carriage for producing relative step-by-step movement between said computing wheels and said master wheel; of a set of nine numeral 45 keys controlling the step-by-step movement
- of the carriage and solely governing the extent of rotation of the master wheel; certain of said keys paired for operation in succession to print two-digit numbers and cause their computation by said master wheel on 50 said ultra-decimal wheel; a case-shift mechanism; and means controlled by said case-shift mechanism for causing said paired keys, when so operated, to successively compute on said ultra-decimal wheel digits 55 which differ from those of the number actually printed but whose combined computation exactly totals such number; said ultra-decimal wheel constructed to remain operatively engaged by said master wheel during 60 the operation of both keys.
25. In a typewriting and computing machine, the combination, with a plurality of computing wheels, including an ultra-decimal wheel, a master wheel for driving the 65 computing wheels *seriatim*, and a carriage for producing relative step-by-step movement between said computing wheels and said master wheel; of a set of nine numeral keys controlling the step-by-step movement 70 of the carriage and solely governing the extent of rotation of the master wheel; certain of said keys paired for operation in succession to print two-digit numbers and cause their computation by said master wheel on 75 said ultra-decimal wheel; and means for causing said paired keys, when so operated, to successively compute on said ultra-decimal wheel digits which differ from those of the number actually printed but whose com- 80 bined computation exactly totals such number; said ultra-decimal wheel constructed to remain operatively engaged by said master wheel during the operation of both keys.
